UNITED STATES PATENT OFFICE.

JOSEPH S. MEAD, OF MILWAUKEE, WISCONSIN.

DESIGN FOR A NECK AND CHEST PROTECTOR.

No. 39,612.

Specification for Design.

Patented Oct. 6, 1908.

Application filed June 17, 1908. Serial No. 439,069. Term of patent 7 years.

To all whom it may concern:

Be it known that I, JOSEPH S. MEAD, a citizen of the United States, residing at Milwaukee, county of Milwaukee, and State of Wisconsin, have invented a new, original, and ornamental Design for Neck and Chest Protectors, of which the following is a specification, reference being had to the accompanying drawing, forming part thereof.

The figure is a plan view of a neck and chest protector, showing my new design.

I claim:

The ornamental design for a neck and chest protector as shown.

JOSEPH S. MEAD.
